J. PETROVITCH.
MILK BOTTLE RETAINER.
APPLICATION FILED JULY 28, 1916.

1,204,818.

Patented Nov. 14, 1916.

UNITED STATES PATENT OFFICE.

JOSEPH PETROVITCH, OF TORONTO, ONTARIO, CANADA.

MILK-BOTTLE RETAINER.

1,204,818.

Specification of Letters Patent. Patented Nov. 14, 1916.

Application filed July 28, 1916. Serial No. 111,904.

To all whom it may concern:

Be it known that I, JOSEPH PETROVITCH, a subject of the Czar of Russia, and a resident of the city of Toronto, in the county of York, in the Province of Ontario, Canada, have invented certain new and useful Improvements in Milk-Bottle Retainers, of which the following is the specification.

My invention relates to improvements in milk bottle retainers and the object of the invention is to devise a simple means whereby a milk bottle, when left at the door of a consumer, can be locked in position by the milk man so as to prevent its removal by any unauthorized person and it consists essentially of the following arrangement and construction of parts hereinafter more particularly explained by the following specification.

Figure 1, is a general perspective view of my device shown in the open position. Fig. 2, is a similar view to Fig. 1 showing my device in the locked position with the upper portion of the milk bottle shown in position so as to be secured thereby. Fig. 3, is a plan view of my device with the top cover plate removed and corresponding to the position shown in Fig. 1. Fig. 4, is a similar view to Fig. 3 showing my device in the closed position. Fig. 5, is a sectional view on line $x-y$ Fig. 3. Fig. 6, is a sectional view on line $x'-y'$ Fig. 3. Fig. 7, is a sectional view on line $x''-y''$ Fig. 3. Fig. 8, is a perspective detail of the slide piece.

In the drawings like letters of reference indicate corresponding parts in each figure.

1 indicates a bracket provided with upper and lower lug portions 2 and 3 through which orifices 2^x and 3^x extend through which screws or other suitable securing devices are screwed into a wall or door or other suitable support on which my device is designed to be secured.

4 indicates a casing extending outwardly from the center portion of the bracket 1 and comprising upper and lower plates 4^x and 4['] and side wall portions 5 and 6 separating the upper and lower plates 4^x and 4['] so as to form the hollow interior of the casing.

7 indicates a fork extending forwardly from the casing and preferably formed integral with the lower plate 4['].

4² and 4³ indicate longitudinal grooves

formed in the inner faces of the upper and lower plates 4^x and 4['].

8 indicates a slide piece fitting in the grooves 4² and 4³ so as to be slidable therein. The body of the slide piece 8 is provided with a jaw portion formed by the members 8^x and 8['], the jaw being provided at its base with a V-shaped portion 8².

8³ indicates a cross head secured between the jaw members 8^x and 8['] at their ends.

8⁴ indicates a teat extending inwardly from the end of the slide piece 8, and 8⁵ indicates a teat opposing the teat 8⁴ and extending from the inner end of the hollow casing 4.

9 indicates a compression spring extending between the inner end of the slide piece 8 and the opposing wall of the casing 4 and into which the teats 8⁴ and 8⁵ extend.

One end of the cross head 8³ is provided with a projecting portion 8¹⁵ having an inclined lower face 8⁶.

10 indicates a block secured inside the casing against the back wall thereof.

11 indicates a vertical pin extending through the block 10 and at its lower end into the bottom plate 4['] of the casing 4.

12 indicates a swingable piece having an orifice 12^x through which the pin 11 freely extends. The free end of the piece 12 is designed to swing up and down in a vertical plane.

13 indicates a compression spring fitting into an orifice 13^x formed in the lower plate 4['] of the casing and bearing at its upper end against the lower face of the piece 12. The upper face of the piece 12 is provided with an inclined upper face portion 14 opposing the inclined face 8⁶ of the cross head 8³ when the device is in the open position.

15 indicates a recess formed in the swing piece 12 at the rear of the portion 14 so as to form a shoulder 14^x at the upper end of the inclined face of the portion 14.

16 indicates a notch formed in the side wall 5.

17 indicates a groove formed in the inner face of the upper plate 4^x opposite the notch 16 and terminating at its inner end in an enlargement 17^x arc-shaped in cross section.

18 indicates a groove formed in the piece 12 in alignment with the base of the notch 16.

19 indicates a key, the shank of which is designed to extend through the notch and

groove 17 so that the bit of the key, when the key is in position, fits into the arc-shaped notch 17^x and the shank of the key in the groove 18.

- 5 20 and 21 indicate a pair of semi-circular arms pivoted at 22 and 23 to the upper and lower plates 4^x and 4' of the casing 4. The inner ends of the arms 20 and 21 are provided with inwardly extending portions 24 and 25, the portion 24 having its upper face recessed at 26 and the portion 25 having its lower face recessed at 27, the ends of such recesses being formed arc-shaped eccentric to the center of swing of the arms 20 and 21.
- 10 15 Having described the principal parts involved in my invention I will briefly describe the operation of the same.

When inserting the bottle in the device so as to secure it in position against removal 20 all that it is necessary to do is to insert the neck of the bottle in the fork 7 with the enlarged rim of the bottle above the arms 20 and 21. In this position the bottle is forced inwardly against the end of the slide 25 piece 8 forcing it inwardly against the compression of the spring 9, such inward movement being continued until the cross head 8³ is carried far enough inward to carry the inclined lower face 8⁶ of the portion 8¹⁵ past 30 the inclined face 14, the piece yielding during this operation against the pressure of the spring 13. As soon as the inclined face 8⁶ has passed the inclined face 14 the piece 12 swings upwardly so that the forward edge 35 of the portion 8¹⁵ engages against the shoulder 14^x. During this operation the V-shaped portion 8² of the slide piece 8 forces the inner ends of the arms 20 and 21 formed by the portions 24 and 25 outwardly and the 40 opposite ends of the arms 20 and 21 inwardly together into the position shown in Fig. 4. When the arms 20 and 21 have reached this position they are locked in place by the engagement of the portion 8¹⁵ with 45 the shoulder 14^x as hereinbefore described.

When the purchaser of the milk desires to remove the bottle from the holder all that he has to do is to insert a key into the notch 16 and turn the head of the key 50 in the recess 17^x so that the bit engages with the free end of the piece 12 depressing it against the compression spring 13 and thereby carrying the shoulder 12^x below the portion 8¹⁵. By this means the cross head 8³ 55 is freed and the cross head and slide piece 8, which are formed integral, are carried forwardly in the grooves 4² and 4³. As the cross head 8³ passes forwardly it strikes the arc-shaped ends of the arms 20 and 21 there- 60 by spreading the arms apart into the position shown in Fig. 3. The bottle can then be removed. The key is, of course, then removed by the purchaser of the milk bottle and retained by the purchaser.

65 From this description it will be seen that

I have devised a very simple device for retaining milk bottles in place when they are left at the door of a purchaser so as to prevent their removal by any unauthorized person.

What I claim as my invention is:

1. A milk bottle retainer comprising a main supporting bracket, a pair of pivoted arms designed to surround the neck of the milk bottle, a longitudinally movable bar 75 slidably held in the bracket between the arms, a compression spring normally holding the bar in its outward position, an engaging member carried by the longitudinally movable bar and a co-acting spring pressed 80 engaging member swingably mounted on the bracket and designed to engage with the engaging member of the bar when the bar is moved rearwardly.

2. A milk bottle retainer comprising a 85 bracket, a casing carried by the bracket having an open mouth, a pair of arms adapted to surround the neck of the milk bottle and extending at their inner ends into the mouth of the casing and pivoted therein, a slide bar 90 extending between the pivoted ends of the arms and slidably held in grooves formed in the upper and lower walls of the casing, a cross head carried by the inner ends of the slide bar having a projection extending outwardly from one end having an upwardly rearwardly inclined lower face, a spring pressed pivoted member carried within the casing and having a correspondingly inclined face engaging the inclined face of the 100 cross head and having a recess formed at the rear of such inclined face, a compression spring inserted between the cross head and the back of the casing, and means for drawing the arms together by the inward 105 movement of the slide bar and forcing them apart by the outward movement of the slide bar, and key means for depressing the pivoted member against the spring pressure.

3. A milk bottle retainer comprising a 110 main supporting bracket, a casing having upper and lower walls having longitudinal grooves therein, a spring pressed slide bar 115 slidably held in such longitudinal grooves, a cross head carried by the slide bar, means for automatically locking the slide bar in its inward position against the pressure of the spring, a pair of arms pivoted to the casing, inward extensions to the pivoted arms, a V-shaped portion forming part of 120 the slide bar and extending between the inward extensions of the arms, and means with which the cross head engages when released for forcing the inner ends of the extensions inwardly to open the pivoted arms.

4. A milk bottle retainer comprising a main supporting bracket, a casing having upper and lower walls having longitudinal grooves therein, a spring pressed slide bar 125 slidably held in such longitudinal grooves,

a cross head carried by the slide bar, means 5 for automatically locking the slide bar in its inward position against the pressure of the spring, a pair of arms pivoted to the casing, inward extensions to the pivoted arms having oppositely recessed upper and lower faces designed to overlap when the arms are in the open position, a V-shaped portion forming part of the slide bar extending 10 between such overlapping ends when the slide bar is in the forward position to force such overlapping ends apart by its inward movement, and means at the ends of the inward extensions of the arms 15 with which the cross head engages for forcing the extensions together into the overlapping position when the cross head is released.

5. A milk bottle retainer comprising a

bracket, a casing carried by the bracket 20 having longitudinally grooved upper and lower walls, a spring pressed slide bar held within the longitudinal grooves, a cross head carried by the slide bar, means for automatically locking the slide bar in the inward 25 position, swingable jaw arms pivoted at each side of the slide bar, means for forcing the jaw arms together during the inward movement of the slide bar, and inward extensions to each of the arms having arc-shaped ends 30 eccentric to the center of swing of the arms and with which the cross head of the slide bar engages during its outward movement to force the arms apart.
